UNITED STATES PATENT OFFICE.

CHARLES A. PITKIN, SR., OF SAN JOSÉ, CALIFORNIA.

FRUIT-DRIER.

SPECIFICATION forming part of Letters Patent No. 374,697, dated December 13, 1887.

Application filed April 27, 1887. Serial No. 236,361. (No model.)

To all whom it may concern:

Be it known that I, CHARLES A. PITKIN, Sr., of San José, Santa Clara county, State of California, have invented an Improvement in 5 Fruit-Driers; and I hereby declare the following to be a full, clear, and exact description of the same.

My invention relates to that class of driers for fruit and other materials in which baskets 10 containing the material to be dried are suspended from a rotating wheel mounted within a suitable drying-chamber; and my invention consists in certain improvements in this class of machines, as I shall hereinafter fully describe and claim.

Referring to the accompanying drawings for a more complete explanation of my invention, Figure 1 is a vertical cross-section of my fruit-drier, taken on the line Z Z, Fig. 3. Fig. 2 is 20 a longitudinal section of same on the line y y of Fig. 3. Fig. 3 is a horizontal section taken on line Y Y of Fig. 2.

A is the shell of the drier, in which is mounted a wheel, B, consisting of an axle or 25 shaft, b, and radial arms b'.

Care the tray-carrying baskets, having arms c, suspending them from the rim of the wheel. The rim of the wheel is usually composed of transverse rods b', carried by the end heads or 30 radial arms, and to these rods are hinged the tray-carrying baskets. It is usual to suspend but one basket from a rod; but in some cases two have been attempted; but when two are used the weight is so great as to cause a sagging of the rods, which throws the baskets out 35 of true and causes their corners to come in contact with the radial arms. To avoid this difficulty, I provide central radial arms, D, extending from the axle b, and which practically 40 divide the wheel into two parts, said arms serving to brace rods b' or the rim of the wheel, of whatever character said rim may be. In this way I am enabled to provide a practical double machine which is strong and will 45 not sag in any part. In the bottom portion of the shell is located the heater or stove F, to the back of which are connected the heating pipes f, having the chimney-exit f'.

Above the stove and the heating-pipes, and 50 occupying a horizontal plane completely filling the width of the shell, is a deflecting-plate, G, the length of which, however, is not as

great as that of the shell, its ends stopping short, whereby an opening, g, is formed at the back of the shell and an opening, g', is formed 55 at the front. The rear end of the deflecting-plate is preferably made with a flange, g'', turning upwardly, and its forward end is made with a flange, g'', turning downwardly, the lower edge of said last-named flange coming 60 down to the plane of the top of the stove and provided with apertures and a controlling-damper, g''. This plate, it will be seen, divides the shell into a drying-chamber above 65 and a heating-chamber below.

In the stove end of the shell and on each side of the stove are the walls H, which are separated from the end wall of the shell by a space, h, said walls coming up to the lower edge of the downwardly-turned flange 70 g'' of the deflecting-plate and on a level with the top of the stove. These walls completely traverse the space between the side walls of the shell and the stove or heater, whereby the compartments h are formed, which communicate directly above with the drying-chamber, and through the damper-controlled opening in the flange g'' of the deflecting-plate with the heating-chamber, and I make them communicate with the outside air by means of ports or 80 holes h' through the end wall of the shell, said ports being controlled by valves h''.

The grate-bars of the stove or heater do not come entirely to the feed-door, as my object is to draw as much heat toward the back as possible, thus leaving the compartments h much 85 cooler.

I are the pipes or tubes by which the outer air is admitted to the heating-chamber, said pipes passing through the wall of the shell 90 and through the tops of the compartment-walls H, and thus the outside air may be introduced directly into the heating-chamber.

J is a vertical box forming a passage at the side of the shell. The upper end of this box 95 communicates with the upper portion of the drying-chamber at j, and in its lower end is a controlling-valve, j'.

The general operation of the machine is as follows: Suitable power is applied to rotate 100 the wheel B within the drying-chamber. The cold air passes in through the pipes I and is directed backwardly into the heating-chamber, whereby it is thoroughly heated, and, as the

inner end of the heating-chamber is the highest in point of temperature, it will pass to the opening g left by the deflector-plate at the back of the shell, and will thence go upwardly 5 into the drying-chamber. When it has become saturated with moisture, it circulates downwardly, assisted by the rotation of the wheel, through the drying-chamber, and, finding the cooler front portion of the shell, will pass down o through the opening g' at the front of the deflector-plate, and while a portion of the less heavy air will pass through the damper (if said damper is open) on flange g^3 of the deflector-plate, and back again into the heating- 5 chamber, the larger portion of it will drop down into the compartments h and may be drawn off through the valve-controlled ports h' ; but in case the air is so heavily charged with moisture that it is not desirable to allow any o of it to pass again into the heating-chamber, I close the damper g^4 , so that all the air passes into the compartments h and out through ports h' . That portion of the saturated air which still remains in the top of the drying-chamber 5 will pass through the opening at j and down into the box J , where the thoroughly saturated part may be drawn off through the valve j' .

The advantages of the several novel points o of construction which I have here described may be summed up as follows: The central radial arms D permit me to use a double set of suspended baskets without causing the wheel-rim (of whatever nature said rim may be) to sag. The deflector-plate, separating the heating-chamber from the drying-chamber, provides, by means of its openings at each end, for the proper circulation, while the cooler compartments h at the front of the shell provide for the discharge of such portions of moisture-laden air as may fall down out of the circulation. The box J at the side of the shell provides for drawing off the top moisture without losing any of the still useful hot air within 5 the drying-chamber.

Having thus described my invention, what I claim as new, and desire to secure by Letters Patent, is—

1. In a fruit-drier, a shell and a stove, and o heating-pipes located within its lower portion, in combination with a horizontally-arranged deflecting-plate above the stove and pipes, and

having a flanged outer end, g^3 , said plate dividing the shell into heating and drying chambers, and leaving openings at its inner and outer ends by which the chambers communicate, and short walls formed within the shell on each side of the stove and rising to the plane of its top and to the lower edge of the flange g^3 , whereby the compartments h are formed communicating above with the drying-chamber, and valve-controlled openings through the outer shell communicating with said compartments, substantially as herein described. 55

2. In a fruit-drier, a shell and a stove, and heating-pipes located within its lower portion, in combination with a horizontally-arranged deflecting-plate above the stove and pipes, said plate dividing the shell into a heating and a drying chamber, and leaving openings at its inner and outer ends by which the chambers communicate, the short walls formed within the shell on each side of the stove and rising to the plane of its top, whereby the compartments h are formed directly under the opening at the outer end of the deflecting-plate 70 and communicating with the drying-chamber above, valved openings by which said compartments communicate with the outer air, said deflecting-plate having a downward flange 75 meeting the tops of the short walls and provided with openings, and a controlling-damper, whereby the drying-chamber is separated from or allowed to communicate with the front of the heating-chamber, substantially as herein described. 80

3. In a fruit-drier, a shell having a heater or stove and heating-pipes, as described, in combination with the horizontally-arranged deflecting-plate having the flange g^3 and the openings $g'g$, the compartment-walls within the end of the shell, having their tops meeting the lower edge of said flange, valved openings communicating with the compartments, and cold-air pipes extending through the outer 95 shell and the compartment-walls, substantially as herein described.

In witness whereof I have hereunto set my hand:

CHARLES A. PITKIN, SR.
